[57] CLAIM

The ornamental design for an insect bait station, as shown and described.

DESCRIPTION

FIG. 1 is a perspective view of an insect bait station showing our new design;

FIG. 2 is a top, plan view, with the bottom view being a mirror image thereof;

FIG. 3 is a side elevational view thereof taken from the bottom of FIG. 2; and,

FIG. 4 is a sectional view taken from the plane 4—4 of FIG. 2.

FIG. 1

FIG. 2

FIG. 3

FIG. 4
